UNITED STATES PATENT OFFICE.

JOHN H. BERNHARD, OF McGREGOR, IOWA.

TANK-HEATER.

1,113,185.

Specification of Letter Patent.

Patented Oct. 13, 1914.

Application filed November 20, 1913. Serial No. 802,107.

To all whom it may concern:

Be it known that I, JOHN H. BERNHARD, a citizen of the United States, residing at McGregor, in the county of Clayton and State of Iowa, have invented certain new and useful Improvements in Tank-Heaters; and I do declare the following to be a full, clear, and exact description of the invention, such as will enable others skilled in the art 10 to which it appertains to make and use the same.

This invention relates to improvements in tank heaters, and the main object thereof is to provide a simply constructed device of 15 this character having efficient means for protecting the burner in said heater from rain or wind and from any water of condensation which may be formed in the top of the heating chamber.

With this and other objects in view, the invention resides in certain novel features of construction and combination herein described and claimed and shown in the drawings, wherein:—

Figure 1 is a vertical longitudinal section of my improved heater, and Fig. 2 is a detail vertical section on line 2—2 of Fig. 1.

In the drawings, I have shown my tank heater as comprising a heating chamber 1, 30 a burner 2 disposed therein, a fresh air intake pipe 3 for said heating chamber, a warm air outlet pipe 4 opening into the top of said chamber, and a casing 5 supported by the upper ends of the pipes 3 and 4.

Supported within the heating chamber 1 and spaced from the top thereof by means of a stud 6 and nut 7 thereon, is a dripping plate 8 having a depending apron 9 around its outer edge and being provided with an 35 opening 10, disposed beneath the opening in the outlet pipe 4, said opening being provided with an upwardly and inwardly extending flange 11. The opening 10 and its flange 11 are of less diameter than the 45 opening within the pipe 4 for a purpose to appear.

A fuel feed pipe 12 leads from the burner 2 through the air intake pipe 3, and is provided on its upper end with a funnel 13 50 and a branch 14. A fuel reservoir 15 is supported on the branch 14 and said branch beneath the reservoir 15 is provided with a drip cock 16 adapted to control the flow of fuel from the reservoir 15, through the pipe 55 12 to the burner 2.

The casing 5 is provided with a bottom

17 having a depending flange 17', with a hinged top 18, and a partition 19 having flanges 20 along its opposite sides, said flanges 20 being secured to the casing 5 by 60 rivets 21. By providing the casing 5 with the partition 19 I form a flue 22 and a fuel compartment 23. It will be seen by reference to the drawings, that the warm air outlet pipe 4 passes through the bottom 17 65 into the flue 22, said flue being provided with ventilating holes 24 at its bottom, heat discharging holes 25 near its top and a removable cap 26. The fuel compartment 23, into which projects the upper end of the 70 air intake pipe 12, is provided with a door 27 and a plurality of air inlet holes 28 in its bottom. Rods 29 pass through the pipes 3 and 4 into the opposite flanges of the bottom 17 for securely holding the casing 5 75 in place on the pipes 3 and 4. If desired, I may insert a coil 30 in the upper portion of the heating chamber 1, its inlet end 31 projecting through one side of the chamber at a comparatively low point, and its outlet 80 end 32 passing through the opposite side thereof at a higher point. It is to be understood that the flange 11, being of less diameter than the opening 10, will prevent any condensed moisture from falling from 85 the pipe 4 and entering the heating chamber through the opening surrounded by said flange.

From the foregoing description, taken in connection with the accompanying drawings, 90 the construction and operation of the device will be readily understood without requiring a more extended explanation.

Having thus described my invention, what I claim is:—

1. In a device of the character described, a heating chamber, a burner located therein, and a warm air outlet at the top thereof, a drip plate within said chamber carried by and spaced from the top thereof, said drip 100 plate being provided with an opening beneath said warm air outlet and having an upwardly projecting flange around said opening of a smaller diameter than said warm air outlet.

2. In a device of the character described, a heating chamber, a burner located therein, a fresh air intake for the lower end of said chamber and a warm air outlet from the top thereof, a coil within said chamber and 110 opening through the opposite sides thereof, a drip plate of greater diameter than said

95

105

110

coil disposed within said heating chamber and spaced from the top and sides thereof, said plate having a warm air outlet surrounded by an upstanding flange and a depending apron around its outer edge, said flange being disposed below the warm air outlet from said heating chamber and being of less diameter than the same.

3. The combination with a submergible
10 heating chamber having a burner therein, a
fresh air inlet pipe and a warm air outlet
pipe rising from said chamber, of a casing
having openings in its bottom for the re-
ception of said pipes, and a flange depend-
15 ing from said bottom, rods passing through
said pipes near their upper ends and pro-

jecting through apertures in said flange, an
upright partition in said casing between the
upper ends of said pipes to form a flue and
a fuel compartment, said flue having aper- 20
tures in its bottom and side walls and said
fuel compartment being provided with a
reservoir for supplying fuel to said burner
and air inlet holes in its bottom for fur-
nishing air for said fresh air pipe. 25

In testimony whereof I have hereunto set
my hand in presence of two subscribing
witnesses.

JOHN H. BERNHARD.
